(57) **CLAIM**

The ornamental design for a cover for a biological array holder, as shown and described.

DESCRIPTION

FIG. 1 is a front perspective of an embodiment of a cover for a biological array holder;

FIG. 2 is a back perspective of the cover shown in FIG. 1;

FIG. 3 is a front view of the cover shown in FIG. 1;

FIG. 4 is a back view of the cover shown in FIG. 1;

FIG. 5 is a side view of the cover shown in FIG. 1;

FIG. 6 is a side view of the cover shown in FIG. 1;

FIG. 7 is a top view of the cover shown in FIG. 1; and,

FIG. 8 is a bottom view of the cover shown in FIG. 1.

The broken lines in the drawings are included for the purpose of illustrating portions of the cover for a biological array holder that form no part of the claimed design.
